UNITED STATES PATENT OFFICE.

SIMON P. COTA, OF PORTLAND, OREGON.

CUT-OUT AND RELEASE FOR AIR-BRAKE APPARATUS.

1,164,259.

Specification of Letters Patent. Patented Dec. 14, 1915.

Application filed March 2, 1914. Serial No. 822,018.

To all whom it may concern:

Be it known that I, SIMON P. COTA, a citizen of the United States of America, residing at Portland, in the county of Multnomah and State of Oregon, have invented certain new and useful Improvements in Cut-Outs and Releases for Air-Brake Apparatus, of which the following is a specification, reference being had therein to the accompanying drawing.

This invention relates to air brakes and the principal object of the invention is the production of an efficient means whereby the train crew may be advised as to the condition of the air which is adapted to actuate the air brakes, and will at the same time be advised as to where a break occurs if such a break should occur in the train pipe or brake mechanism.

The present invention is an improvement upon my previous patents bearing Numbers 943,769 and 952,070, and therefore, the improvement in the present invention resides in the means for indicating the point of break by which the train crew may be readily advised so as to efficiently locate the point where the break has occurred in the train pipe in order that the same may be quickly and efficiently repaired.

With these and other objects in view this invention consists of certain novel combinations, constructions, and arrangements of parts as will be hereinafter fully described and claimed.

In the accompanying drawings:—Figure 1 is a perspective view of a portion of the floor of the car with parts thereof being broken away to show the improved cut-out and release mechanism for the air brakes.

Fig. 2 is a central transverse section through the body of a car showing the arrangement of the several pipes and brake mechanism as carried by the car. Fig. 3 is a plan view of the signaling apparatus used for indicating the pressure within the brake cylinder. Fig. 4 is a vertical section through the plunger casing or cylinder. Fig. 5 is a section taken on line 6—6, of Fig. 4. Fig. 6 is an enlarged sectional view taken through the lower end of the piston rod

showing the manner in which the piston head is secured to the piston rod. Fig. 7 is a transverse section through the forward end of the auxiliary reservoir showing the manner in which the drain pipe is connected thereto.

It should be borne in mind that by means of the air and electric devices herein described, the working of the air brakes will cause a signal to be displayed in each car when the brakes are applied so that it can be quickly ascertained if all brakes are properly working.

It should be understood that the indicating devices may be placed in any position or in any portion of the car to suit the convenience of the user without departing from the spirit of the invention, for it is not necessary to limit the position of the device to any particular portion of the car.

By referring particularly to Fig. 4 it will be seen that an electric signaling device is produced which comprises a cylinder 1 having a plunger rod 2 slidably mounted therein. This signaling device as particularly illustrated in Fig. 4 is adapted to work automatically with the air brake system and is controlled by means of the movement of the brake cylinder head 3 mounted in the brake cylinder 4. This system will be controlled at all times in setting and releasing the brakes caused by the engineer or operator, or from a break or leak or any other cause that may reduce the train line or train pipe pressure enough to change the position of the usual triple valve.

The construction of the signal especially illustrated in Fig. 4 is similar to that disclosed in my previous Patent Number 952,070, with the exception of a slight modification of the piston head and cylinder used therewith.

It is, therefore, thought unnecessary to go into the detail explanation of this construction other than to give a general description as to the operation and use of the signal mechanism in connection with that portion of the structure more specifically illustrated in Fig. 1. It has been found through practical experience that where a leak or break in the train pipe occurs and the discovery of this leak is left to the train crew, considerable damage and inconvenience is the result, which requires the stopping of the train in order to ascertain the place or point of leak or break of pipe along the train line or train pipe.

By means of the device more specifically herein described, it should be understood that the train crew will be enabled to be at all times advised as to the defects along the train pipe by consulting and comparing the indicators 5 and 6. The break in the

pipe may be remedied by cutting off the brakes from the car in which the break has occurred and thereby allow the rest of the brakes of the train to efficiently operate without causing any damage to be done by the operation of that portion of the brake mechanism which has been put out of commission by means of the break along the pipe.

10 By referring to Fig. 1 it will be seen that 7 indicates the floor of the car and beneath the floor of the car is suspended the train pipe 8. A branch pipe 9 extends from the train pipe 8 as illustrated in Fig. 1, and this 15 branch pipe 9 carries a cut-out 10 which is actuated by means of a rotating rod 11, having its upper end squared as indicated at 12 for receiving an operating tool. The upper end 12 is mounted within a socket 13 as illustrated in Fig. 1, and as is more 20 clearly described in detail in my previous Patent Number 943,769. The pipe 9 also carries the usual triple valve 14, and this triple valve 14 communicates with the brake cylinder 15. The pipe 9 has a pipe communication 16 with the auxiliary reservoir 17.

25 The auxiliary reservoir 17 is provided with a drain pipe 18, which drain pipe carries a drain cock 19 at one end, which cock 30 is operated by means of an operating rod 20, having its upper end seated within the socket 13 so as to allow the train crew to have access thereto for opening the cock 19 when it is desired to drain the auxiliary 35 reservoir 17 from moisture or other substance which has accumulated therein.

30 A gage pipe 21 is connected to the train pipe 8 and extends under the car and this gage pipe 21 carries a vertically extending 40 pipe 22, which pipe supports a gage 6 for indicating the amount of pressure along the train pipe 8. As stated above, the gage 6 may be placed in any desired position upon the car to suit the convenience of the train 45 crew.

45 As has been stated, the cylinder 1 comprises part of the mechanism for operating an electric signal so that the attention of the train crew may be called to the gage 5 which serves as a visible signal and is of 50 special value as a night signal. For daylight use the gage in itself would ordinarily be sufficient, as it is supported by the branch pipe in a conspicuous position. In order 55 to provide for using the gage 5 independently, the service pipe 23 may be provided with a plug valve 24 above the branch pipe 25, which branch pipe leads to the gage 5 so as to cut off communication with the 60 cylinder 1 when it should be so desired.

65 The cylinder 1 is provided with a detachable cap 26 at its lower end for engaging the pipe 23, and this cap 26 is provided with a socket 27 formed therein for receiving the lower end 28 of the piston rod 2. The casing

1 is provided with a filler block 29 having an aperture 30 formed therein through which the piston rod 2 extends. A buffer block 31 is mounted within the cylinder 1 and through this buffer block 31 also extends the plunger rod 2.

A plunger head 32 is carried upon the lower end of the plunger rod 2, and this plunger head 32 comprises a pair of sections between which is mounted a washer 33. This washer may be formed of leather or other suitable material. The lower end of the plunger head 32 is provided with a tapering threaded aperture 34 in which is threaded a pin 35, and it should be understood that by threading the pin 35 into the lower end of the plunger rod 2 the same will be spread so as to force the washer 33 outwardly and cause the same to more firmly engage the head of the cylinder 1.

85 A coil spring 36 is mounted upon the plunger rod 2 and engages the filler block 29 for exerting a downward pressure upon the plunger head 32 against the pressure of the air adapted to be admitted therein. An electric contact mechanism 37 is carried by the upper end of the plunger rod 2 for closing the circuit through the wires 38 and 39 for operating the signal 40. It will be seen that the buffer block 31 will constitute a means for limiting the upper movement of the plunger head 32, thereby relieving considerable pressure from the spring 36 and preventing injury thereto.

90 From the foregoing description it will be seen that a very efficient means has been produced whereby a cut-out may be obtained for releasing the air brakes when a train is in motion.

95 By means of the present invention the train crew may be readily advised whether the pressure gage 6 and air signal 5 is caused from a defection of the train line caused by the engineer in stopping his train or from a leak as by comparing these two 100 gages the trainmen will be fully advised as to the condition of the pressure of the train line. As for instance, provided the gage 6 should register one hundred pounds and the air signal 5 should register fifteen or twenty 105 pounds, the trainmen would have positive assurance that a leak had occurred or a sticky triple valve was located upon the car in which the indication appeared upon the pressure gage 6 carried by that car. The 110 train crew by passing from car to car may readily read the gages and as soon as one gage is found to register in the manner above described he will know where to locate the trouble which has occurred to the 115 train line or pipe. If a leak should occur in the train pipe, this leak may be easily remedied by cutting off the brakes from the car in which the leak should occur by the 120 operation of the valve 10 as above described. 125

As above stated, it should be further understood that the present invention may be applied in any position upon the car to suit the convenience of the train crew or suit the 5 design of the manufacturer of the car.

It should be understood that the present invention is also efficient for locating the point at which dynamiting occurs in the cylinders and valves due to the accumulation of 10 grit or other foreign substance which may have entrance to the valves and cylinders. Dynamiting, of course, greatly hampers the operation of the brakes and by allowing the train crew to readily locate the point at 15 which the dynamiting occurs a great advantage has been produced.

Having thus described the invention, what is claimed as new, is:—

1. A device of the class described comprising a brake cylinder, an electric contact member, a signal operating casing, a signal operating mechanism carried by the said casing a plunger rod carried by said casing and adapted to actuate said signal operating 20 mechanism, a plunger head carried by said casing and mounted upon said plunger rod, said plunger rod provided with means for binding said head thereon, means for exerting a downward pressure upon said 25 plunger head, a filler block positioned in the upper end of said casing, a compression 30

member engaging said filler block, and said compression member adapted to be engaged by said plunger head for limiting the upward movement thereof.

35

2. A device of the class described comprising a brake cylinder, an electric contact member, a signal operating casing, a signal operating mechanism carried by the said casing a plunger rod carried by said casing 40 and adapted to actuate said signal operating mechanism, a plunger head carried by said casing and mounted upon said plunger rod, said plunger rod provided with means for binding said head thereon, a filler block positioned in the upper end of said casing, a compression member engaging said filler block, a spring carried by said plunger rod for exerting a downward pressure upon said plunger head, and said compression means 45 provided with means for receiving said spring and said compression means also constituting means for limiting the upward movement of said plunger head within said casing.

55

In testimony whereof I hereunto affix my signature in presence of two witnesses.

SIMON P. COTA.
